UNITED STATES PATENT OFFICE.

FREDERIC AUMONIER, OF LONDON, ENGLAND.

DESIGN FOR WALL-PAPER.

SPECIFICATION forming part of Design No. 22,803, dated September 26, 1893.

Application filed August 28, 1893. Serial No. 484,264. Term of patent 3½ years. Patented in England March 3, 1893, No. 208,521.

To all whom it may concern:

Be it known that I, FREDERIC AUMONIER, (trading as WM. WOOLLAMS & CO.,) a subject of the Queen of Great Britain, and a resident of 110 High Street, near Manchester Square, London, England, have invented a new and original Design for Wall-Paper, (patented in Great Britain on the 3d of March, 1893, No. 208,521,) of which the following is a specification.

This design for wall paper is represented on the annexed drawing and consists of peony like flowers surmounted by an oak like leaf the spaces being filled with drooping plants having berries in clusters.
